ROUND CORNER CASE MAKING MACHINE

James E. Stringer, Central City, Nebr.

Application October 19, 1950, Serial No. 191,046

14 Claims. (CL. 154—41)

1

The present invention relates to bookbinding and more particularly it is an object of this invention to provide a machine that will secure a covering to the cardboard used in book binding.

In the art of custom bookbinding the coverings are of flexible material and are to be placed across one side of and stuck by glue or cement around the edges of a cardboard backing. There have been many unsuccessful attempts to construct a machine capable of automatically folding the covering around the edges of the material. Until now there have been no machines built capable of automatically sticking down the four corners of the covering.

It is therefore an object of this invention to provide a machine capable of doing this.

Another object is to provide a machine capable of sticking down the sides of the covering material automatically as well as sticking down the corners.

Another object is to provide a machine for automatically applying book covering material rapidly and with uniform appearance.

Yet another object of the invention is to provide a device for the purpose described which is sturdy and durable in construction, reliable and efficient in operation, and relatively simple and inexpensive to manufacture, assemble, and utilize.

Other and further objects and advantages of the present invention will be apparent from the following detailed description and claims and are illustrated in the accompanying drawings which, by way of illustration, show the principles of the invention and a mode in which I have contemplated applying those principles.

Other embodiments of the invention embodying the same or equivalent principles may be used and structural changes may be made as desired by those skilled in the art without departing from the present invention and the purview of the appended claims.

In the drawings:

Figure 1 is a top plan view of the device of this invention and the platform upon which it is mounted.

A portion of the pulley belt is broken away and an electric motor to power the machine is not shown for convenience of illustration.

Figure 2 is a top plan view of the spring guide used with the invention together with a portion of cardboard which is being covered. The spring guide rod and spring are broken away and a roller wheel is shown in dotted lines.

Figure 3 is a view-in-section taken along the

line 3—3 of Figure 2. A roller wheel is shown partially broken away and the spring guide rod and spring are shown broken away.

Figure 3A is a top plan view of a portion of the rollers and chain. The view is indicated by the line 3A—3A of Figure 5. This partial view of the rollers and chain illustrates the alignment of the rollers with respect to the alignment of the chain. This alignment is not illustrated in the other figures because of the reduced scale and drafting difficulty.

Figure 4 is a front elevation of the entire invention. A work turntable and a portion of the platform are broken away to reveal parts behind. An electric motor is shown in dotted lines.

Figure 5 is a view-in-section taken along lines 5—5 of Figure 1. A side frame member of the roller assembly, portions of the chain rollers, the upper portion of the clamping mechanism, and 20 a portion of the pulley wheel are broken away and shown by dotted lines.

Referring to the drawings for a more particular description and as best shown in Figures 1 and 4, the book covering mechanism 10 is mounted upon a rectangular platform 12 which latter is composed of five spaced apart transversely disposed angle iron beams 14.

The beams 14 are welded at each end to a further pair of spaced apart longitudinally disposed angle iron beams 16.

A flat metal plate 18 is welded or otherwise secured over approximately two-thirds of the rectangular area formed by the beams 14 and 16 whereby certain portions of the book covering mechanism 10 may extend below the level of the plate 18 and through the rectangular uncovered area 20 on one side of the platform 12 as later described.

An axle shaft 22 is longitudinally disposed 40 above the uncovered area 20 and is provided with bearings 24 near each end thereof which latter are each maintained in a yoke 26. The ears 28 of the yokes 26 are provided with a threaded aperture 30. One of four threaded bolts 32, transversely disposed with respect to the axle 22, is threaded into each aperture 30 and the bolts extend inwardly to bear against the sides of the bearings 24 to adjustably align the axle 22. A nut 34 is provided for each bolt 32 and the nuts 34 are disposed against the sides of the yoke ears 28 to lock the bolts 32 in position.

The two yokes 26 are each provided with two oppositely disposed flange footings 36. Each footing 36 is disposed above a cylindrical metal post 38 and secured thereto by a machine bolt

3

40 which latter extends through an aperture in each footing 36 and is threaded into the top of each post 38.

The posts 38 rest upon the transversely disposed angle iron beams 14 and are each provided at their bottoms with a threaded pin 40 which latter extends through apertures provided through the transverse angle iron beams 14. Nuts 42 are disposed on the threaded pin 40 for securing the posts 38 to the angle irons 14.

The inward portion of the shaft 22 is secured to a large pulley wheel 44 which latter is in transverse alignment with the pulley wheel 46 of an electric motor 48 located below the platform 12 and shown in dotted lines in Figure 4.

A pulley belt 50 encircles the two wheels 44 and 46 for transmitting rotary motion to the axle shaft 22. A further pulley wheel 52 is secured to the axle shaft 22 at a position between the bearings 24 and closely adjacent the innermost bearing 24 for purposes later described.

An elongated rectangular shelf 60, transversely disposed and spaced above the platform 12, is positioned between the yokes 26 and below the axle shaft 22 with an outer end overhanging 25 the uncovered area 20.

The shelf 60 is supported upon two narrow parallel metal blocks 62 which are positioned on the platform plate 18 and are located one on each transverse side of the shelf 60.

The shelf 60 and blocks 62 are secured together and secured to the platform plate 18 by machine screws which latter are not shown in order to more clearly illustrate other parts.

As best shown in Figure 5, a lower short longitudinally disposed shaft 64, located directly below and aligned with the described axle shaft 22, is supported beneath the overhanging portion of the shelf 60 by means of two spaced apart bearing blocks 66.

The bearing blocks 66 are secured to the under-side of the shelf 60 by machine screws which latter are not shown in order to better illustrate other parts.

The bearing blocks 66 are provided with axially aligned apertures 68 through which the shaft 64 extends. The innermost end of the shaft 64 is secured to a small pulley wheel 70 located below the pulley wheel 52. A pulley belt 72 encircles the pulley wheels 70 and 52 in order to drive the lower shaft 64.

Located between the bearing blocks 66 and secured to the shaft 64, a worm screw 74 is located which is in mesh with a horizontally disposed gear wheel 76.

A vertical bearing sleeve 78 is disposed through an aperture 80, which latter is located at the center of the shelf 60. The sleeve 78 is secured to the shelf 60 by welding or other suitable means.

The lower end of a vertical shaft 82 is secured to the gear wheel 76. The vertical shaft 82 extends through the sleeve 78. The upper end of the shaft 82 is secured to a pair of horizontally disposed knurled wheels 84 one located above the other.

The knurled wheels 84 receive rotary motion from the worm gears 74 and 76 in order to revolve a small turntable upon which the covering material is placed, as later described.

Two spaced apart parallel elongated bars 90 extend inwardly at right angles from the upper axle shaft 22. The bars 90 are located above the center of the shelf 60. The outer ends of the bars 90 adjacent the axle 22 are each pro-

4

vided with an axially aligned transverse aperture. Two short bearing sleeves 94 are provided, one disposed in each aperture 92.

The axle 22 is disposed through the sleeves 94 and through a small sprocket wheel 96 which latter is secured to the axle 22 in between the two parallel bars 90.

The opposite ends of each bar 90 are provided with axially aligned transverse apertures 98 through which extend a small axle pin 100. A further small sprocket wheel 102 is secured to the axle pin 100 and mounted between the bars 90.

Equally spaced apart from themselves and equally spaced apart from the two sprocket wheels 96 and 102 are two transverse spacers 104 welded transversely in between the bars 90 for strengthening the structure.

A roller chain 106 encircles the two sprocket wheels 96 and 102 and, as best shown in Figure 4, each outer link 108 on each side of the chain is provided with an ear or tang 110 which is integral with the link 108 and extends upwardly therefrom at a right angle with respect to the axis of the roller chain 106.

Each tang 110 is provided with an aperture 112 through which an axle pin 114 is disposed. The axle pin 114 extends between each pair of tangs 110.

A small roller wheel generally indicated at 116 comprises a covering folding portion 115 which latter is made of a substantially incompressible material such as steel and a smoothing portion 117 for flattening the covering, which latter is made of rubber or similar material. The roller wheel 116 is mounted on the axle pins 114 between each parallel tang 110.

The steel folding portion 115 is disc-shaped and is provided with a knife edge 118 around its outer perimeter. It is also provided with an elongated cylindrical outwardly protruding hub which latter is journaled about the axis pin 114. The rubber portion 117 is cylindrical in shape and is disposed about the outer perimeter of the hub of the steel portion 115.

The perimeters of the rubber rollers 116 are provided with integral transversely disposed elongated teeth 117' making alternate ridges and furrows across the rollers 116.

As shown in Figure 3A, each tang 110 is not in alignment with the link 108 with which it is integral. With respect to or in comparison with an exact alignment of the tangs 110 to the links 108, as indicated by the line 118', the tangs 110 have been twisted or turned slightly in a counter-clockwise direction to the alignment indicated by the line 119. The roller wheels 116 are aligned with the twisted or turned tangs 110.

The purpose of providing slightly clockwise-turned tangs 110 and roller wheels 116 is to compensate for the relative motion between the rollers 116 and a turntable which carries the book-binding material being sealed together. The turntable will be described later.

As best shown in Figures 1 and 5, a metal block 120 is secured alongside the innermost parallel bar 90 by welding or other suitable means. A machine bolt 122, secured to the center of the block 120, extends horizontally and outwardly therefrom.

An elongated vertical rod 124 is provided with a nut 126 threaded adjacent to its lower end. The rod 124 is threaded into a tapped hole in the shelf 60 and extends therefrom upwardly to bear against the underside of the machine screw 122. The rod 124 thereby provides a sup-

5

port for the parallel bars 120 and attached mechanism which is adjustable in height by turning the rod further in or out of the shelf 60.

An integral rectangular portion 128 of the block 120 extends downwardly therefrom and is provided with a horizontal slot 130 disposed parallel with the two bars 90.

A thin plate 132 is placed overlapping the slot 130 and is secured to the rectangular portion 120 by two metal screws 134 which are best shown in Figure 1. The slot 130 slidably carries an elongated square rod 136 which latter extends through the slot 130.

As best shown by Figures 2 and 3, the inwardly extending end of the square rod 136 is welded to the backside of a covering material upturning member or guiding spoon 138. The spoon 138 is approximately L-shaped in cross section, having an upstanding wall 140 rounded into a forwardly extending flat portion 142.

A horizontal, generally rectangular, thin plate 144 is integrally formed to the lower end of the wall 140 and extends under the forward end of the rod 136.

A narrow block or shoe 146 is cemented to the upper surface of the plate 144 and positioned directly beneath the rubber rollers 116. The outer end of the shoe 146 is beveled to form an incline whereby the rollers 116, upon traveling over the shoe, become compressed before rolling onto the covering material as the latter is being sealed together as later described.

An elongated compression spring 148 disposed about the square rod 136 abuts the block 128 and the back side of the upstanding wall 140 in order to urge the guiding spoon 138 forward for reasons later described.

An annular boss 160 provided with a flange 162 is secured to the metal plate 18 of the platform 12 by bolts 163.

A vertical post 164 is secured into the center of the boss 160 by welding or other suitable means. The boss 160 and post 164 are located on the same side of the platform 12 as the axle shaft 22 and at the corner of the platform 12.

A jointed turntable supporting frame will now be described.

Two spaced apart beams 166 extend inwardly over the platform 12, one from the top of the post 164 and one from the bottom.

Both beams 166 are provided at each of their ends with vertically disposed bearing holes 168. The post 164 extends through those two of the holes 168 which are disposed through the inward ends of the beams 168. An elongated vertical axle pin 170 extends through the two holes 168 and in the outward ends of the beams 166.

Two spaced apart upright braces 172 extend inbetween the beams 166 and are welded thereto. A diagonal brace 173 extends from the top of one upright brace 172 to the base of the other brace 172 to strengthen the framework.

A sleeve 174 is rotatably disposed about the pin 170 inbetween the beams 166. An elongated horizontal pipe 176, welded to the lower end of the sleeve 174, is disposed above the surface of the platform 12 and extends in front of the shelf 60.

A further pipe 178 welded to the lower end of the sleeve 174 extends at an angle upwardly over the horizontal pipe 176.

A short, horizontal pipe 180 welded to the top of the sleeve 174 extends to and is welded to the pipe 178.

Welded to the top of the pipe 178 a further short length of pipe 182, aligned with and dis-

75

6

posed above the lower described pipe 176, extends in front of the shelf 60.

A square bearing block 184, provided with a vertical hole 186, is welded to the end of the pipe 182. Another square bearing block 188 is welded to the end of the lower pipe 176 and is provided with a hole 190 which latter is axially aligned and vertically below the hole 186 of the block 184.

A vertical rod 192 provided with a knob 194 at its top is disposed through the hole 190 in the top block 184. A circular clamp 195 is rotatably secured to the lower end of the rod 192.

A cotter pin 196 is disposed through a horizontal aperture 198 provided transversely through the rod 192 above the clamp 194. A compression spring 200, disposed about the rod 192, abuts the top bearing block 186 and lodges against the cotter pin 196 for urging the clamp 195 and rod 192 downwardly at all times.

As best shown in Figures 1 and 5, a backing member or turntable 210 is provided with a horizontally disposed rectangular plate 212. The corners of the plate 212 are rounded. A side wall, or downwardly extending flange 214 of the turntable 210 is integrally formed to, and extends downwardly from, the perimeter of the plate 212.

A vertically disposed post 216 is welded underneath and at the center of the plate 212. The post 216 extends downwardly from the plate 212 and is disposed through the hole 190 in the lower block 188. A nut 218 is threadedly disposed about a threaded lower end of the post 216 to rotatably secure the post 216 to the lower block 188.

As best shown in Figure 5, a wide rubber facing 220 extends around the perimeter of the turntable 210 to provide a surface against which the two knurled wheels 84 turn without slipping.

A flat metal bar 222 is normally transversely disposed across the inner end of the shelf 60. A machine bolt 224, provided with a washer 226, is disposed through an aperture at one end of the bar 222 and secured into the upper side of the shelf 60, whereby the bar 222 is able to pivot from one end. A further machine bolt 228 is secured to the other end of the bar 222, to which is attached a tension spring 230. The spring 230 extends to a threaded shank eyebolt 232 at the opposite end of the shelf 60.

The eyebolt 232 is disposed through an aperture 234 provided in an upstanding short post 236. A nut 238 is threaded to the end of the eyebolt 232 and drawn down against the post 236 in order to tighten the spring 230. A machine bolt 240 extends upwardly through a suitable aperture provided through the shelf 60, and is threaded into the lower end of the post 236.

Disposed within the turntable 210 opposite the two knurled wheels 84, a large metal roller wheel 242 is provided which is rotatably mounted upon a short vertical axle 244.

The axle 244 is welded or otherwise secured to the center of the pivot plate 222, whereby the tension of the spring 230 urges the metal roller wheel 242 against the sidewall flange 214 of the turntable 210 and forces the turntable against the knurled wheels 84.

A thin metal backing pan or plate 250, rectangular in shape and having rounded corners, is secured upon a smaller plate 252 of similar shape, although thicker. The plate 252 is secured to the upper surface at the center of the turntable and serves to space the backing plate 250 above the turntable 210. As best

shown in Figures 2 and 3, the thin metal backing plate 250 extends over the forwardly extending portion 142 of the guide spoon 138.

A rectangular piece of the sandpaper 254 is glued to the upper surface of the metal plate 250 to provide a surface upon which to place a covering 256 and the cardboard 258 to be covered.

In operation, the covering 256 is pre-cut to overlap the size of the cardboard 258 to be covered and placed upon the sandpaper top of the plate 250. The shape and size of the cardboard 258 and covering 256 is similar to the shape and size of the backing pan or plate 250. The clamp 195 is lowered to hold the material in place upon the turntable 210 by the pressure of the spring 200.

The electric motor 48 is turned on causing the elongated shaft 64 together with the worm gear 76 to revolve.

The knurled wheels 84 driven by the worm gear 76 bear tightly against the rubber band 214 of the turntable 210, causing it to revolve in a counterclockwise direction, as shown by the arrow 269 in Figure 2.

Before placing the work on the machine the covering 256 is coated with glue. The cardboard is laid on it and the assembly is then placed under the clamp 195. The overlapping edge of the covering 256 is turned upwardly by the guide spoon 138 before passing in front of the rubber rollers 116.

The rubber rollers 116 and the chain 106 revolve in a clockwise direction as shown in Figure 5. Each successive roller 116 passes up and off the tensioning block or shoe 146 and rolls approximately transverse across the overlapping edge of the covering 256, thereby sealing the covering 256 to the perimeter of the cardboard 258.

Since the rollers 116 are turned slightly counterclockwise, they will not skid or skuff the covering 256 as they roll across the overlapping edge portion of the covering 256.

After a full rotation of the turntable, the clamp 195 is raised by the knob 194, the covered cardboard is removed and the process is repeated.

At times when a large cardboard is to be covered, a large backing pan or plate 250 is substituted for the one formerly used. Variations in shape and size are used as needed.

This machine has provided a machine for folding flexible covering material about stiffer material automatically for performing this operation more economically than has ever been heretofore possible.

From the foregoing description, it is thought to be obvious that a round corner case making machine constructed in accordance with my invention is particularly well adapted for use, by reason of the convenience and facility with which it may be assembled and operated; and it will also be obvious that my invention is susceptible of some change and modification without departing from the principles and spirit thereof, and for this reason I do not wish to be understood as limiting myself to the precise arrangement and formation of the several parts herein shown in carrying out my invention in practice, except as claimed.

I claim:

1. A machine for folding the edge portions of a covering around the edge of a piece of relatively stiff material comprising: a frame; a backing member having a flat surface for receiving said covering thereagainst, said backing member

having a down-turned flange on the under side thereof, said flange having an outer side having a shape in a view looking downwardly from said flat surface of a contour parallel to the outer edge of said piece; means mounting said backing member on said frame such that it is free to move with respect to said frame in all directions in a plane in parallelism with said flat surface; clamp means for holding said piece against said covering when said covering is disposed on said flat surface; a rotating drive member mounted on said frame, said drive member being disposed against the outer side of said flange and drivably engaged therewith for causing said backing member to move in a path complementary to the contour of the outer edge of said piece; a roller disposed on the inward side of said flange; means securing said roller wheel to said frame and urging said roller wheel toward said drive member; up-turning means for causing the outer edge portion of said cover to be bent upwardly from said surface; a plurality of rollers; and means for causing said rollers to pass alternately across said backing member while pressing thereagainst, said rollers each moving across said backing member from the outside thereof toward the inner side thereof transversely of the path of said backing member movement, and said rollers each moving across said backing member at a point disposed closely in front of said covering up-turning means with respect to the direction of movement of that portion of said backing member which is closest to said up-turning means.

2. A machine for folding the edge portions of a covering around the edge of a piece of relatively stiff material comprising: a frame; a backing member having a flat surface for receiving said covering thereagainst; means mounting said backing member on said frame such that it is free to move with respect to said frame in all directions in a plane in parallelism with said flat surface; clamp means for holding said piece against said covering when said covering is disposed on said flat surface; means for causing said backing member to move in a path complementary to the contour of the outer edge of said piece; up-turning means for causing the outer edge portion of said cover to be bent upwardly from said surface; a plurality of rollers; and means for causing said rollers to pass alternately across said backing member while pressing thereagainst, said rollers each moving across said backing member from the outside thereof toward the inner side thereof transversely of the path of said backing member movement, and said rollers each moving across said backing member at a point disposed closely in front of said covering up-turning means with respect to the direction of movement of that portion of said backing member which is closest to said up-turning means.

3. A machine for folding the edge portions of a covering around the edge of a piece of relatively stiff material comprising: a frame; a backing member having a flat surface for receiving said covering thereagainst, said backing member having a down-turned flange on the under side thereof, said flange having an outer side having a shape in a view looking downwardly from said flat surface of a contour parallel to the outer edge of said piece; means mounting said backing member on said frame such that it is free to move with respect to said frame in all directions in a plane in parallelism with said flat surface; clamp means for holding said piece against said cover-

ing when said covering is disposed on said flat surface; a rotating drive member mounted on said frame; said drive member being disposed against the outer side of said flange and drivably engaged therewith for causing said backing member to move in a path complementary to the contour of the outer edge of said piece; a roller disposed on the inward side of said flange; means securing said roller to said frame and urging said roller toward said drive member; up-turning means for causing the outer edge portion of said cover to be bent upwardly from said surface; and means for causing said covering to be folded around the edge of said piece and pressed against that side of said piece which is opposite said surface for causing adhesive to stick said folded edge portion of said covering to said opposite side of said piece.

4. A machine for folding the edge portions of a covering around the edge of a piece of relatively stiff material comprising: a frame; a backing member having a flat surface for receiving said covering thereagainst; means mounting said backing member on said frame such that it is free to move with respect to said frame in all directions in a plane in parallelism with said flat surface; clamp means for holding said piece against said covering when said covering is disposed on said flat surface; means for causing said backing member to move in a path complementary to the contour of the outer edge of said piece; an up-turning member having a surface inclinedly disposed with respect to the path of movement of said backing member, said inclined surface being closer to said path at that end of said inclined surface which is disposed rearwardly in the direction of movement of adjacent portions of said backing member and farther from said path at its other end; and means for causing said covering to be folded around the edge of said piece and pressed against that side of said piece which is opposite said surface for causing adhesive to stick said folded edge portion of said covering to said opposite side of said piece.

5. A machine for folding the edge portions of a covering around the edge of a piece of relatively stiff material comprising: a frame; a backing member having a flat surface for receiving said covering thereagainst; means mounting said backing member on said frame such that it is free to move with respect to said frame in all directions in a plane in parallelism with said flat surface; clamp means for holding said piece against said covering when said covering is disposed on said flat surface; means for causing said backing member to move in a path complementary to the contour of the outer edge of said piece; up-turning means for causing the outer edge portion of said cover to be bent upwardly from said surface; a plurality of rollers; and means for causing said rollers to pass alternately across said backing member while pressing thereagainst, said rollers each moving across said backing member from the outside thereof toward the inner side thereof transversely of the path of said backing member movement, said rollers each moving across said backing member at a point disposed closely in front of said covering upturning means with respect to the direction of movement of that portion of said backing member which is closest to said up-turning means, and said rollers each having a circumferential surface provided with a plurality of alternate ridges and furrows extending thereacross in parallelism with its axis.

6. A machine for folding the edge portions of a covering around the edge of a piece of relatively stiff material comprising: a frame; a backing member having a flat surface for receiving said covering thereagainst; means mounting said backing member on said frame such that it is free to move with respect to said frame in all directions in a plane in parallelism with said flat surface; clamp means for holding said piece against said covering when said covering is disposed on said flat surface; means for causing said backing member to move in a path complementary to the contour of the outer edge of said piece; up-turning means for causing the outer edge portion of said cover to be bent upwardly from said surface; means for causing said covering to be folded around the edge of said piece and pressed against that side of said piece which is opposite said surface for causing adhesive to stick said folded edge portion of said covering to said opposite side of said piece.

7. A machine for folding the edge portions of a covering around the edge of a piece of relatively stiff material comprising: a frame; a backing member having an approximately flat surface for receiving said covering thereagainst; means mounting said backing member on said frame such that it is free to move with respect to said frame in all directions in a plane in parallelism with said flat surface; clamp means for holding said piece against said covering when said covering is disposed on said flat surface; means for causing said backing member to move in a path complementary to the contour of the outer edge of said piece; upturning means for causing the outer edge portion of said cover to be bent upwardly from said surface; at least one roller, said roller having an end edge axis-surrounding portion of its periphery formed of hard substantially incompressible material, the axis-surrounding remainder of said roller periphery being formed of resilient compressible material, said resilient portion of said periphery having alternate ridges and furrows extending parallel to the axis of said roller; means for causing said roller to pass across said moving backing member while pressing against said covering, said passing of said roller being in a path from the outer edge of said material toward the inner portion thereof; and means for causing said roller to return to a position for a repetition of said passing movement, said roller not being in contact with said covering on its return motion.

8. A machine for folding the edge portions of a covering around the edge of a piece of relatively stiff material comprising: a frame; a backing member having an approximately flat surface for receiving said covering thereagainst; means mounting said backing member on said frame such that it is free to move with respect to said frame in all directions in a plane in parallelism with said flat surface; clamp means for holding said piece against said covering when said covering is disposed on said flat surface; means for causing said backing member to move in a path complementary to the contour of the outer edge of said piece; upturning means for causing the outer edge portion of said cover to be bent upwardly from said surface; at least one roller, said roller having an end edge axis-surrounding portion of its periphery formed of hard substantially incompressible material, the axis-surrounding remainder of said roller periphery being formed of resilient compressible material; means for causing said roller to pass across said moving

backing member while pressing against said covering, said passing of said rollers being in a path from the outer edge of said material toward the inner portion thereof; and means for causing said roller to return to a position for a repetition of said passing movement, said roller not being in contact with said covering on its return motion.

9. A machine for folding the edge portions of a covering around the edge of a piece of relatively stiff material comprising: a frame; a backing member having an approximately flat surface for receiving said covering thereagainst; means mounting said backing member on said frame such that it is free to move with respect to said frame in all directions in a plane in parallelism with said flat surface; clamp means for holding said piece against said covering when said covering is disposed on said flat surface; means for causing said backing member to move in a path complementary to the contour of the outer edge of said piece; upturning means for causing the outer edge portion of said cover to be bent upwardly from said surface; at least one roller, said roller having a disc-shaped folding portion at one side, means for causing said roller to pass across said moving backing member while pressing against said covering, said passing of said rollers being in a path from the outer edge of said material toward the inner portion thereof, said roller passing being in a path fixed with respect to said frame and transverse with respect to the direction of movement of those portions of said backing member disposed nearest said roller at the time of first roller contact with said covering; and means for causing said roller to return to a position for a repetition of said passing movement, said roller not being in contact with said covering on its return motion.

10. A machine for folding the edge portions of a covering around the edge of a piece of relatively stiff material comprising: a frame; a backing member having an approximately flat surface for receiving said covering thereagainst; means mounting said backing member on said frame such that it is free to move with respect to said frame in all directions in a plane in parallelism with said flat surface; clamp means for holding said piece against said covering when said covering is disposed on said flat surface; means for causing said backing member to move in a path complementary to the contour of the outer edge of said piece; upturning means for causing the outer edge portion of said cover to be bent upwardly from said surface; at least one roller; means for causing said roller to pass across said moving backing member while pressing against said covering, said passing of said rollers being in a path from the outer edge of said material toward the inner portion thereof, said roller passing being in a path fixed with respect to said frame and transverse with respect to the direction of movement of those portions of said backing member disposed nearest said roller at the time of first roller contact with said covering; and means for causing said roller to return to a position for a repetition of said passing movement, said roller not being in contact with said covering on its return motion.

11. A machine for folding the edge portions of a covering around the edge of a piece of relatively

stiff material comprising: a frame; a backing member having an approximately flat surface for receiving said covering thereagainst; means mounting said backing member on said frame such that it is free to move with respect to said frame in all directions in a plane in parallelism with said flat surface; clamp means for holding said piece against said covering when said covering is disposed on said flat surface; means for causing said backing member to move in a path complementary to the contour of the outer edge of said piece; upturning means for causing the outer edge portion of said cover to be bent upwardly from said surface; at least one roller, said roller having an end edge axis-surrounding portion of its periphery formed of hard substantially incompressible material, said end edge portion having a circular periphery of a dull-knife-edge shape, the axis-surrounding remainder of said roller periphery being formed of resilient compressible material; means for causing said roller to pass across said moving backing member while pressing against said covering, said passing of said rollers being in a path from the outer edge of said material toward the inner portion thereof; and means for causing said roller to return to a position for a repetition of said passing movement, said roller not being in contact with said covering on its return motion.

12. In a case making machine, the combination which comprises a mounting platform, a horizontally disposed turntable journaled on said platform, a backing plate positioned on said turntable, a substantially L-shaped spoon having an arcuate face mounted on said platform and positioned at one side of said turntable, said backing plate positioned to receive a covering sheet, a sheet of relatively stiff material adapted to be positioned on said covering sheet, a clamping member for clamping said sheet of relatively stiff material upon said covering sheet and backing plate, an endless chain positioned to travel transversely across an edge of said sheet of relatively stiff material resilient means for urging said clamping member toward said covering sheet, rollers carried by said chain and positioned to coat with said spoon to fold the edge of said covering sheet against said sheet of relatively stiff material, means rotating said turntable, and means actuating said endless chain.

13. A case making machine as described in claim 12, wherein discs having knife edges are positioned at one end of each of said rollers carried by the endless chain.

14. A case making machine as described in claim 12, wherein said turntable is provided with a depending flange and the rotating means therefor includes knurled vertically positioned wheels outside of the flange coating with a resiliently mounted roller wheel acting against the inside of the flange.

JAMES E. STRINGER.
